HAROLD B. ROSENDAHL, OF MINNEAPOLIS, MINNESOTA, ASSIGNOR TO WATERS-
GENTER COMPANY, OF MINNEAPOLIS, MINNESOTA, A CORPORATION OF MINNESOTA

DRAWER CLOSURE

Application filed June 7, 1932. Serial No. 615,837.

This invention relates to new and useful improvements in drawer closures and more particularly to a drawer closure operating mechanism.

5 An object of the invention is to provide a simple and inexpensive mechanism adapted for use in connection with a drawer provided with a suitable closure, whereby said closure may be elevated relatively to the 10 drawer to partially open the closure and permit air circulation through the drawer.

A further object is to provide in combination with a drawer adapted to be supported within a closed chamber, a suitable 15 closure therefor having means for supporting it independently of the drawer, and means being provided exteriorly of the cabinet for relatively moving said closure out of sealing relation with the open top of 20 said drawer without opening the drawer chamber.

A further object is to provide in combination with a food preserving cabinet having a food storage chamber therein, a suitable 25 drawer adapted to support food stuffs in said chamber, and said drawer having a closure adapted to be floatingly supported thereon in sealing relation, and means being provided for bodily vertically moving the 30 drawer into sealing relation with the closure, when the drawer reaches its normal position within the chamber, and said means also causing the drawer to move out of engagement with the closure, when the drawer 35 is moved from its normal position.

Other objects reside in the means provided for supporting the drawer within the compartment and whereby said drawer will be bodily moved into engagement with the 40 closure, when it reaches the limit of its inward movement; in the means for supporting the closure independently of the drawer and whereby when the closure is relatively translated in one direction, and upward movement will be imparted thereto to move it 45 out of sealing relation with the drawer; in the means provided whereby the closure will be floatingly supported upon the drawer in sealing relation, when the drawer assumes a 50 position within the chamber; in the novel

construction of the closure supporting and operating mechanism whereby the closure is supported independently of the drawer within the chamber, and whereby the closure may conveniently be moved into and out of sealing relation with the drawer when the latter is in its normal position within the closed chamber of the cabinet; and in the specific construction of the closure operating mechanism which comprises telescoping members, one of which is rotatably mounted in suitable threads provided in a fixed support, and the other member being received in threaded engagement with said rotatable member and having an operative connection with the drawer closure, and the threaded connection between said members being such that when said rotatable member is rotated in its support and relatively axially moved therein, said second member will 70 be relatively axially translated in said rotatable member in the same direction, whereby the closure may be quickly moved into or out of sealing relation with the drawer.

Other objects of the invention will appear 75 from the following description and accompanying drawings and will be pointed out in the annexed claims.

In the accompanying drawings, there has been disclosed a structure designed to carry 80 out the various objects of the invention, but it is to be understood that the invention is not confined to the exact features shown as various changes may be made within the scope of the claims which follow.

In the drawings:

Figure 1 is a vertical sectional view of a portion of a cabinet, showing the drawer in its normal closed position, the closure being shown in closed position;

Figure 2 is a view similar to Figure 1 showing the drawer partially withdrawn from the cabinet and the drawer open;

Figure 3 is a detail view on the line 3—3 of Figure 1, showing the means for supporting the drawer within the cabinet and also the means for supporting the closure independently of the drawer;

Figure 4 is an enlarged detail sectional view showing the general construction of 100

the operating mechanism for the drawer closure;

Figure 5 is a cross sectional view on the line 5—5 of Figure 4; and

5 Figure 6 is a detail sectional view on the line 6—6 of Figure 4, showing the finger knob 49 pulled out.

In the construction of food preserving cabinets, such as are often used in places where 10 food is served, it is desirable that means be provided whereby the food containing drawers of the cabinet may be sealed so as to prevent moisture from escaping from the food supported therein. It is also desirable that 15 means be provided whereby the closure may, if desired, be slightly opened so as to permit the escape of moisture from the food contained in the chamber of the cabinet, without opening the drawer chamber to the atmosphere, and it is to this particular feature, and 20 also the means for supporting the drawer, that the present invention relates.

In the selected embodiment of the invention here shown, for purposes of disclosure, 25 there is illustrated in Figures 1 and 2, a portion of a cabinet 2 comprising insulated walls 3, 4, 5, and 6, which define a chamber 7 adapted to receive a suitable drawer 8, the walls of which are spaced from the corresponding walls of the chamber 7, so as to provide an air space around the drawer. The front wall 9 of the drawer is shown provided with forwardly extending members 11 to the outer ends of which is secured a suitable panel 12 provided with an annular flange 13 adapted to be seated against the outer surface of the front wall 5 when the drawer is closed. The panel 12 is adapted to be received within an opening 14 provided in the front wall 5 of the cabinet and through which the drawer 8 is movable.

40 Fixed rails or tracks 15 are secured to the side walls 16 of the cabinet by suitable brackets 17, as shown in Figure 3. Relatively 45 smaller rails or tracks 18 are secured to the side walls of the drawer and upon the rear end portions of these latter rails, a pair of wheels or rollers 19 are mounted. These 50 rollers are adapted to travel upon the fixed rails 15 secured in the chamber 7.

At the front end of the drawer, adjacent to the opening 14, there is provided a pair of similar wheels or rollers 21 which are 55 suitably supported upon the walls of the chamber 7 by suitable means, not shown. The wheels 21 are engaged by the rails 18 of the drawer 8, as will readily be noted by reference to Figures 1 and 2.

60 By thus supporting the drawer within the chamber 7, the latter may be freely moved into and out of the chamber 7 in very much the same manner as the drawer in an ordinary filing cabinet. The rails 15, it will be noted by reference to Figure 3, are provided with 65 horizontally disposed flanges 22 and 23 be-

tween which the rollers 19 travel. A suitable stop, not shown, is provided for limiting the outward movement of the drawer.

A suitable drawer locking mechanism is 70 provided at the front end of the drawer and comprises a spring-actuated latch 20 pivotally supported upon a bracket 24 secured to the front wall 9 of the drawer and having a suitable spring 25 constantly urging it in an upward direction so as to cause the curved 75 face 26 thereof to lockingly engage the inner corners 27 of the drawer opening 14, when the drawer is closed. An operating handle 28 is pivotally mounted upon the panel 12 of the drawer and has a pair of arms 29 extending through suitable openings in the panel and supporting a bar 31 which is adapted to engage the depending portion 32 of the latch 20, to thereby move the latter out of locking 80 engagement with the corner 27 of the opening 14. The latch portion 20 is pivotally and adjustably secured to a complementary portion 33 to provide means for adjusting the curved 85 face 26 with respect to the front wall 9 of the drawer in such a manner that when the drawer is in its normal closed position, as shown in Figure 1, the latch will hold the flange 13 of the panel 12 firmly against the outer face of the wall 5 to seal the opening 14.

An important feature of this invention resides in the novel construction of the closure 90 34 and the means for supporting the same within the chamber 7 independently of the drawer 8. As shown in Figures 1 and 2, the closure 34 is preferably of sheet metal and is provided at its edges with a bead 35, box-like 95 in cross-section, and having its bottom face 36 adapted to engage the upper face of an outwardly turned flange 37 provided upon 100 the drawer.

Suitable brackets 38 are secured to the closure and extend downwardly therefrom at 105 opposite sides thereof and have inclined slots 39 adapted to receive suitable pins 41, which 110 may be fixedly secured to suitable plates 42, here shown interposed between the brackets 17 and the tracks 15, as best shown in Figure 3. When the closure is in the position shown in Figure 1, it will be floatingly supported 115 upon the flange 37 of the drawer, it being noted that the pins 41 are then spaced from the upper edges of the guide slots 39, so that the entire weight of the closure will be supported directly upon the drawer.

To thus cause the closure to be floatingly supported upon the drawer, when the latter is in its normal closed position, means is provided for vertically elevating the drawer when it reaches the limit of its inward movement, as shown in Figure 1. To thus elevate the drawer, each track 15 may be provided with a raised portion or hump 43, and the rails or tracks 18 secured to the side walls 125 of the drawer are provided with similar de- 130

pending portions or humps 44. The raised portions 43 and depending portions 44 are so spaced apart lengthwise of the drawer, that when the drawer is in its normal position shown in Figure 1, the rollers 19 at the rear of the drawer will be engaged with the raised portions 43, and the portions 44 at the forward end of the drawer will be engaged with the rollers 21, thereby causing the drawer to be bodily elevated so that its flange 37 will engage the bead 35 of the closure 34, and lift the closure out of engagement with the pins 41, so that its entire weight will be supported upon the flange 37 of the drawer. As soon as the drawer is initially moved forward in the operation of withdrawing it from the chamber 7, the rollers 19 and 21 will move out of engagement with their respective portions 43 and 44 of the rails 15 and 18, respectively, thereby causing the drawer to be lowered out of engagement with the closure, as shown in Figure 2. The drawer may then be conveniently withdrawn from the chamber 7 without frictionally engaging the closure during its movement into and out of the chamber.

Means is also provided for relatively elevating the closure so that it may be moved out of sealing relation with the drawer, when the latter is in its normal position, as shown in Figure 1. Such means is best shown in Figure 4 and comprises telescoping members, one of which is in the form of a threaded sleeve 45 received in threaded engagement with a plate 46 shown secured to the inner surface of the front wall 5 of the cabinet. The sleeve 45 has a stem 47 extending outwardly through an opening 48 provided in the wall 5, and a finger knob 49 is secured to the outer end of the stem whereby it may be conveniently rotated. In order to permit axial movement of the sleeve 45 in the plate 46, the opening 48 in the wall 5 is made sufficiently large to receive the sleeve 45. To provide a neat and finished appearance, a suitable filler block 51 is mounted upon the stem 47 between the end of the sleeve 45 and the finger knob 49. This block is prevented from relatively rotating in the opening 48 by having a flat face 52 on one side thereof which engages a correspondingly flattened face provided in the bore of the opening 48. A suitable finish plate 53 is shown secured to the outer face of the wall 5, and has an opening 54 through which the filler block 51 may travel when the sleeve 45 is axially translated. The word "Open" may be marked or impressed in the surface of the flat face 52 of the block 51 to indicate to the attendant when the drawer closure is in open position.

A connecting rod 55 has a hooked terminal 56 pivotally secured to the closure 34, as shown in Figures 1 and 2. The opposite end of this rod is loosely received in a socket 50 provided in one end of a threaded member

or plug 57, which is received in threaded engagement with a socket 58 provided in the sleeve 45. The member 57 is held against rotation by a pin 59 passing through the end thereof and the rod 55, as clearly shown in Figure 4. It is to be understood that the connection between the rod 55 and socket 50 is such as to permit slight up and down movement of the opposite end of the rod, so as to prevent the rod from binding in the socket 56, when the rod is moved up and down with the closure, as indicated by the full and dotted lines in Figure 1.

By reference to Figure 4, it will be noted that the exterior threads of the sleeve 45 are shown cut right hand, while the threads in the socket 58 are cut left hand. By thus cutting these threads, when the knob 49 is rotated counter-clockwise, the sleeve 45 will be axially translated in an outward direction in the wall 5, and at the same time, the member 57 will be relatively axially translated in the sleeve 45 by reason of its threaded connection therewith. Because of the threads in the socket 58 being cut opposite to the exterior threads of the sleeve 45, the member 57 will travel at relatively greater speed than the sleeve 45, which greater speed is transmitted to the closure 34, whereby it may be quickly moved out of sealing relation with the drawer. Conversely, when the knob 49 is rotated clockwise, the sleeve will be moved inwardly and the member 57 will be moved in the same direction at a relatively greater speed so as to quickly return the closure to its closed position upon the drawer.

By thus constructing the operating mechanism for the closure, the latter may be quickly moved into or out of sealing relation with the drawer by simply turning the finger knob 49. It is to be understood that when the closure is moved in a direction towards the front wall 5 of the cabinet, the upper edges of the inclined guide slots 39 will engage the pins 41 and thereby elevate the closure and, conversely, when the closure is moved in the opposite direction, or away from the front wall 5, the guide slots will permit the drawer to be lowered to its normal position to be engaged by the drawer, when the latter is moved into its normal position, shown in Figure 1.

Thus, it will be seen that by the employment of the novel closure operating mechanism herein disclosed, the closure may be quickly and conveniently moved into or out of sealing relation with the drawer top without having to pull the drawer out of the chamber 7. The closure, it will be noted, is supported within the chamber independently of the drawer, and is not movable with the drawer when the latter is moved in and out of the chamber 7. Also, because of the closure being floatingly supported upon the drawer top, the connection between the drawer and closure will be substantially

sealed when the drawer is in its normal position, as shown in Figure 1, which is important in that if any slight irregularities should occur in the alignment of the rails which support the drawer, such misalignment will not effect the seating of the closure upon the drawer.

I claim as my invention:

1. In a cabinet having a chamber therein, a drawer mounted for movement in said chamber, a closure for the drawer, means in said chamber adapted to support the closure independently of the drawer, and permitting it to sealingly engage the drawer, when the latter is moved into the chamber, and means for elevating the closure in parallel relation to the drawer top to break the seal between it and the drawer.
2. In combination with a closed cabinet having suitable supports therein a drawer mounted for movement upon said supports, a closure for the open top of said drawer, means movably supporting said closure, and means for elevating said drawer when it is moved into its normal position to thereby cause it to engage and elevate said closure, whereby the latter will be floatingly supported thereon in sealing relation.
3. A cabinet having a chamber therein provided with suitable guides, a drawer supported on said guides and adapted to be moved into and out of said chamber, a closure for the drawer, means for independently supporting said closure within the chamber, means by which said closure is floatingly supported upon the drawer when the latter is in normal position, and means exteriorly of the cabinet for relatively elevating said closure to break the seal between it and the drawer top.
4. A cabinet having a chamber therein provided with suitable rails, a drawer movably mounted on said rails and adapted to be moved into and out of said chamber, a closure for said drawer positioned within the chamber, inclined guides for supporting the closure independently of the drawer, and means for relatively moving said closure upon said guides to move it out of engagement with the upper portion of the drawer.
5. A cabinet having a chamber therein provided with suitable rails, a drawer movably mounted on said rails and adapted to be moved into and out of the chamber, a closure for the drawer supported within the chamber and adapted for vertical movement, and means on said rails for bodily elevating the drawer when it reaches the limit of its inward movement to thereby cause it move into sealing relation with said closure.
6. A cabinet having a chamber therein provided with suitable rails, a drawer movably mounted on said rails and adapted to be moved into and out of said chamber, a clo-

sure for the drawer, means for supporting said closure independently of the drawer and permitting relative vertical movement thereof, means independent of the drawer for moving the closure out of sealing relation therewith, and means for bodily elevating the drawer when it reaches the limit of its inward movement to thereby move it into sealing relation with said closure, and whereby when the drawer is initially moved in a direction to withdraw it from the chamber, the drawer will automatically be lowered out of engagement with said closure.

7. A cabinet having a chamber therein, a drawer movably mounted in said chamber and provided with a closure, means for supporting the closure independently of the drawer, and an operating mechanism for said closure comprising telescoping members, one of said members being movably mounted in a fixed support and the other having an operative connection with the closure, and means by which when said first mentioned member is axially translated, said second mentioned member will be relatively axially translated therein in the same direction to operate the closure.

8. A cabinet having a chamber therein, a drawer movably mounted in said chamber and provided with a closure, means for supporting the closure independently of the drawer, and an operating mechanism for said closure comprising telescoping members, one of said members being movably mounted in a fixed support and the other having an operative connection with the closure, and threaded means for relatively axially translating said second mentioned member in said first mentioned member to move said closure into and out of sealing relation with the drawer.

9. A cabinet having a chamber therein, a drawer movably mounted in said chamber and provided with a closure, means for supporting the closure independently of the drawer, and an operating mechanism for said closure comprising telescoping members, one of said members being received in threaded engagement with a support and having means whereby it may be conveniently rotated to impart axial movement thereto, the other of said members having an operative connection with the closure and being received in threaded engagement with said rotatable member, and the thread connection between said members being such that when the rotatable member is rotated and axially translated in its support, the other of said members will be relatively axially translated in said rotatable member in the same direction to thereby quickly move the closure into and out of sealing relation with the drawer.

10. A cabinet having a chamber therein provided with suitable opening, a drawer movably mounted in said chamber and having means for closing said opening to seal

the chamber, a closure for the drawer within said chamber, inclined guides for supporting the closure independently of the drawer, and an operating mechanism for horizontally moving said closure whereby said guides will cause it to move into or out of sealing relation with the drawer, said operating mechanism comprising a threaded sleeve received in threaded engagement with a wall of the cabinet and having an operating member positioned exteriorly of the cabinet whereby said sleeve may be rotated to relatively axially translate it in said wall, and a member received in threaded engagement with said sleeve and having an operative connection with said closure, the threaded connection between said sleeve and said member being such that when the sleeve is rotated and axially translated in one direction, said member will be relatively axially translated in said sleeve in the same direction, thereby causing the drawer to be quickly moved into or out of sealing relation with said drawer.

11. A cabinet having a chamber therein provided with a suitable opening, a drawer movably mounted in said chamber and having means for closing said opening to seal the chamber, a closure for the drawer, means for supporting the closure within said chamber and independently of the drawer, and an operating mechanism for moving said closure into and out of sealing relation with the drawer, said operating mechanism comprising a threaded sleeve received in threaded engagement with a support in a wall of the cabinet and having an operating member positioned exteriorly of the cabinet whereby said sleeve may be rotated to relatively axially translate it in said wall, a non-rotatable plug received in threaded engagement with said sleeve and having an operative connection with said closure, and the threaded connection between said plug and said sleeve being such that when the sleeve is rotated and axially translated in its supports, said plug will be relatively axially translated in said sleeve in the same direction, whereby the drawer may be quickly moved into or out of sealing relation with said drawer.

50 In witness whereof, I have hereunto set my hand this 1st day of June, 1932.

HAROLD R. ROSENDAHL.
